R. M. BEMISDORFER

ADJUSTABLE HUB DUST GUARD AND MOUNTING

Filed Sept. 12, 1925

FIG. 1.

FIG. 2.

FIG. 3.

FIG. 4.

Robert M. Bemisdorfer
Inventor

By Adam C. Fisher

Attorney

UNITED STATES PATENT OFFICE.

ROBERT M. BEMISDORFER, OF DES MOINES, IOWA.

ADJUSTABLE HUB DUST GUARD AND MOUNTING.

Application filed September 12, 1925. Serial No. 55,977.

To all whom it may concern:

Be it known that ROBERT M. BEMISDORFER, a citizen of the United States, residing at Des Moines, in the county of Polk and State 5 of Iowa, has invented certain new and useful Improvements in Adjustable Hub Dust Guards and Mountings, of which the following is a specification.

This invention pertains to dust guards for 10 the front wheels of automobiles, and one object of the invention is to provide a simple, practical and efficient guard to prevent dust or other foreign matter from entering the inside of the wheel hub and grinding between 15 the spindle of the axle and the said hub, thereby abrading and damaging the bearing surfaces.

Another object is to provide an attachment of the kind described which may be 20 readily mounted in place without taking off the wheel of the vehicle.

In the drawing—

Figure 1 is a vertical transverse section 25 of the device as applied to the front wheel hub and adjacent steering gear of an automobile;

Figure 2 is a top plan view of the detached device;

Figure 3 is a side elevation;

Figure 4 is an end view.

In carrying out this invention I provide upper and lower semi-circular hub shields 1 and 2, of flexible sheet metal, the same being slotted along each edge with a plurality of 35 slits 3 directed straight inwardly, thereby forming rows of tabs 10 and 11. Supporting arms 4 are extended from these shields, the same having forks 5 adapted to embrace the steering knuckle 6. Two latch bars 7 are provided, the same having bolt holes 8 in their ends adapted to engage the ends of the forks 5. The outer ends of the forks are threaded to engage nuts 9. These shields are readily mounted in place over 40 the inner end of the wheel hub 12 by bolting the forks over the steering knuckle, as shown in Figure 1. The inwardly turned edges of the upper shield are preferably allowed to overlap the outwardly turned

edges of the lower shield, as shown at 13, 50 thus locking the shields together. The tabs at one side, as 10, are then bent downwardly approximately to the wheel hub 12; suitable packing 14 is then stuffed into the box so formed by the semi-circular shields, and the other rows of tabs 11 are then bent down, thus securely locking the packing in place. This packing effectually prevents dust and grime from entering the hub.

While I have herein described a certain 60 specific manner and method of constructing and assembling the elements of my invention, it is understood that I may vary from the same in minor details, not departing from the spirit of my invention, so as best to construct 65 a practical device for the purpose intended, as defined in the appended claims.

I claim:

1. In combination with the front wheel hub and adjacent steering knuckle of an 70 automobile, a device of the kind described, comprising semi-circular shields of flexible material adapted to fit over the inner end of the hub at the top and bottom thereof, the said shields having rows of tabs formed 75 along their edges adapted to be bent downwardly for forming a packing box; and means for securing the shields to the steering knuckle.

2. In a device of the kind described, semi-circular hub shields adapted to enclose the inner end of a vehicle hub, the said shield having rows of tabs formed along their edges adapted to be bent downwardly to 80 form a packing box.

3. In a device of the kind described, semi-circular hub shields adapted to enclose the inner end of a vehicle hub, the said shields having rows of tabs formed along their edges adapted to be bent downwardly to 85 form a packing box, and the inwardly turned edges of the upper shield being adapted to overlap the inwardly turned edges of the lower shield, for locking the shields together.

In testimony whereof I affix my signature.

ROBERT M. BEMISDORFER.
